MULTIPLE SHOT AERIAL SALUTE

Achillo Fabrizio, Havre de Grace, Md.

Application June 15, 1932. Serial No. 617,296

4 Claims. (Cl. 102—20)

This invention relates to pyrotechnic salutes, and more particularly to a multiple shot aerial bomb.

The object of the invention is to provide an improved multiple shot aerial salute in which the individual bombs will be of the same detonation, and which can be manufactured cheaper and with greater facility than articles of this kind have heretofore been made.

According to the invention the multiple shot aerial salute comprises a housing member with individual barrels retained therein, a single fuse extending around the bottoms of these barrels, and a charge of explosive mixture contiguous thereto, a salute or bomb, fuse downward, in each of said barrels, and means for closing the upper end of said barrels.

The drawing illustrates an embodiment of the invention, and the views therein are as follows:

Figure 1 is a top plan view of the housing member showing the barrels and the individual fuse in the bottom of the same.

Figure 2 is a side view of the completed article.

Figure 3 is a vertical sectional view of the article of Figure 2, and is taken on a line similar to the line 3—3 of Figure 1, and

Figure 4 is a bottom plan view of the housing member with the base removed, and shows the bottom of the barrels.

As illustrated in the drawing, the multiple shot aerial salute has a base 11 which is hollowed out to provide an angular flange 12 and into which is glued or otherwise fastened the housing member 13. This housing in the present instance is shown as being round, but it may be of any desired shape.

Within the housing member 13 is the series of tubes or barrels 14 which are arranged to fill the said barrel without deformation. The base 11 is made of wood or other like material, while the housing member 13 and tubes 14 may be made of rolled paper or pasteboard.

At a distance from the bottom of each of the barrels 14 is a disk 16 while a fuse 17 enters the housing member through the opening 18 and is then laced through the bottom disks 16 in the bottoms of each of said barrels, as shown in Figures 1, 3 and 4.

The distance between the bottoms of the barrels 14 and disk 16 will determine the space of time between the explosions of the successive bombs, the portion of the fuse 19 necessarily having to pass from the disk 16, down around the

The upper ends of the barrels 14 are closed, as desired, such as by means of the plug 24.

It will be readily seen that as the outer end 26 of the fuse is ignited (see Figure 1), the fuse will first ignite the explosive mixture 21 in the barrel A, which will immediately catapult the bomb or salute 22 through the upper end of the same, and into the air, and as the fuse 23 of said salute would naturally be ignited from the explosive mixture 21, the fuse will have burned down into the explosive mixture 27 of the salute when the same is high in the air and the salute will, therefore, explode with a loud detonation.

It will be apparent that the explosive mixture in the barrel A will be ignited when the fuse 70 burns to the point 28 and as the fuse continues to burn through the bottom of said barrel and around through its part 19, (see Figure 3) and to the point 29 (see Figure 1), it will ignite the explosive mixture in the barrel B, thereupon catapulting the bomb or salute from that barrel into the air.

In like manner the salutes or bombs from the barrels C, D and E will be catapulted and exploded.

With a construction of this kind it is unnecessary to make any distinction in the salutes, as to the location of the explosive charge, etc., or in the location and height of the explosive charge in the bottoms of the barrels.

The article is easy to assemble and can, therefore, be made at low cost.

Of course, the multiple shot aerial bomb illustrated and described herein may be varied in many ways without departing from the invention 90 herein set forth and hereafter claimed.

I claim:—

1. A multiple shot aerial salute comprising a housing member, individual barrels in said housing, a bomb in each of said barrels and having its 95 fuse extending downwardly, a fuse in the bottoms of said barrels arranged to successively ignite the fuse of said bombs, and explosive mixture in the bottoms of said barrels for catapulting said bombs.

2. A multiple shot aerial salute comprising a base, a housing member secured thereto, individual barrels in said housing, a bomb in each of said barrels and having its fuse extending downwardly, a fuse in the bottoms of said barrels arranged to successively ignite the fuse of said bombs, and explosive mixture in the bottoms of said barrels to catapult said bombs.

3. A multiple shot aerial salute comprising a housing member, individual barrels within the 110

bottom of the barrel, and up into the disk 16 of the adjacent barrel.

An explosive mixture 21 is placed in the bottom of each of the barrels, while a bomb or salute 22 is placed on top of the explosive charge and with its fuse 23 in contact therewith.

housing, a fuse extending progressively through the bottoms of the barrels, a bomb in each of said barrels and having its fuse extending downwardly, explosive mixture in each of said barrels and contiguous to the fuse therein, and closure means for said barrels.

4. A multiple shot aerial salute comprising a housing member, individual barrels within the housing, a fuse extending progressively through the bottoms of the barrels and having one end extending to the outside of said housing member, a bomb in each of said barrels and having its fuse extending downwardly, explosive mixture in each of said barrels and contiguous to the fuse therein, and closure means for said barrels.

CERTIFICATE OF CORRECTION.

Patent No. 1,922,156.

August 15, 1933.

ACHILLO FABRIZIO.

It is hereby certified that error appears in the printed specification of the above numbered patent requiring correction as follows: Page 2, lines 1 to 6 inclusive, strike out the words and paragraph—"bottom of the barrel, and up into the disk 16 of the adjacent barrel.

An explosive mixture 21 is placed in the bottom of each of the barrels, while a bomb or salute 22 is placed on top of the explosive charge and with its fuse 23 in contact therewith." and insert the same to follow line 55, on page 1; and that the said Letters Patent should be read with this correction therein that the same may conform to the record of the case in the Patent Office.

Signed and sealed this 12th day of February, A. D. 1935.

Leslie Frazer
